FILTER-AMPLIFIER COMBINATION

Henri Chireix, Paris, France

Application March 30, 1929, Serial No. 351,424,
and in France April 4, 1928

13 Claims. (Cl. 179—171)

The art of electric filters has been known for a number of years. It is known that an electric filter consists of an assembly of "cells" or units either similar or dissimilar, closed in both directions upon what has come to be called the characteristic impedance of the unit. This quantity plays a very important part in the theory of filters, whether the point is to define the conditions of output of the filter in the filtering range, or to associate in series groups of units of a different type.

It is also known that if the losses (or dissipation) occasioned in the filter are neglected, the relationship of the energies at the input and output ends of the filter is unity throughout the filtering range, provided the filter is closed upon the characteristic impedance hereinbefore referred to. Finally, when calculating the latter it is found that, inside the filtering range, this quantity varies within wide limits, say, between zero and infinity, or, between zero and finite value, then to fall back to zero; or, else between infinity and a finite value, then to rise again to infinity. It is as a consequence quite difficult, if not impossible, to operate and use filters of the known kind under the required conditions.

The object of the present invention is to provide an amplifier having the ultimate properties of a band filter (regularity of amplification inside the band to be passed, and rapidly growing attenuation outside these limits), though, for reasons of its very nature, different both in theoretical and practical regard from filters properly so-called.

The said result is attained by choosing for the output circuit of an amplifier tube an impedance network or chain (hereinafter to be designated as the filter group), one part of which is associated with and acts upon the grid circuit of a second tube either directly (if the separate source of supply for the different stages are acceptable), or through the well-known means of a leak resistance, whenever the same supply sources are to be employed. Fundamentally speaking the number of stages may be unlimited, though in practice it is found that three are ample, especially when (and this is the most interesting case) the filter groups constituting the plate circuit of the various tubes are proportioned in a different manner in the various stages. The characteristics which distinguish the arrangement here disclosed from the known type of filter are as follows:

(1) The filter group works on an open circuit, in other words, furnishes no energy (the leakage

resistance or leak which may have a value of several megohms has only the object of determining the potential of the grid of the following tube); hence, no characteristic impedance is here involved, and the relationship between the input and output energies of the group is infinitely high.

(2) The internal dynamic resistance of the amplifier tube and the resistance feeding the high potential to the plate (Fig. 1) exercise a definite action owing to their reduced value (parallel resistance of these two elements). The value of this resistance is decisive for the quality of the filtering process (regularity of amplification inside the filtering zone) and the width of the band passed or transmitted. This resistance, however, cannot be compared with the characteristic impedance of known filters for the following two reasons:

(a) Its value should be constant for all frequencies, whereas the characteristic impedance of a filter varies inside wide limits within the filtering band, and becomes a purely imaginary quantity in the regions of attenuation.

(b) Variations, even when quite small in value, result, on the contrary, in considerable variations in the width of the band passed and in the attenuation curve for the attenuated zone or band. In known filters, on the other hand, the width of the filtering zone depends only upon impedances, and the characteristic impedance plays no part at all in the attenuated zone.

(3) It is possible to unite without any inconvenience, or without adoption of special precautionary means, filtering groups of different nature, such association being always by means of a multiple-electrode tube, no reflection having to be expected because of the unilateral characteristic or action of these tubes.

The fundamental principles underlying my invention and the manner of applying the same so as to provide a structure embodying the invention will now be set forth in the accompanying drawing and the following detailed description in which,

Fig. 1 shows the arrangement of a filter amplifier comprising three filtering groups according to this invention.

Fig. 2 shows the electric equivalent of a simple filter group, type I.

Fig. 4 shows the electric equivalent of a composite filter group of the "cut-off" frequency type (type II).

Figs. 3 and 5 illustrate the attenuation curves for types I and II, respectively.

Referring to Fig. 1, the potential to be am-

plified and filtered is fed to the grid-filament circuit of a triode 2 across the terminals of a resistance 1. All triode filaments are heated by the common battery 3. The triode grids have a negative bias supplied from battery 4, and the triode plates are fed from the common battery 5 through resistances 6.

The resistances 6 are preferably rheostats, indeed, the value of these resistances governs, as will be seen later, the width of the band and the regularity of the current in the filtering zone.

7, 8, 9, 10 constitute a filter group (I) of type I with no cut-off frequency. It consists of a series resonant circuit (capacity 7, inductance 8) tuned to the geometric medium frequency of the filter, this circuit being connected in series with another circuit (inductance coil 9, capacity 10) parallel or anti-resonant, and likewise tuned to the geometric mean frequency of the filter.

20 The potential set up across the terminals of this circuit is fed to triode 11 by the well-known assembly comprising coupling capacity 12 and leak resistance 13. The latter should have a rather large value (say, several hundred thousand ohms or several megohms) so as not to constitute an appreciable shunt for the circuit 9-10. Elements 7', 8', 9', 10', 14, 15 connected in the output circuit of triode 11 constitute a filter group II, of type II, with cut-off frequency.

30 This group also comprises a series resonant circuit 7'-8', one parallel or anti-resonant circuit 9'-10', and a second similar circuit 14-15, each of these three circuits being tuned to the geometric mean frequency of the filter. The potential set up at the terminals of the complex parallel or anti-resonant circuit 9'-14-10'-15 is transferred to triode 16 whose plate circuit consists likewise of a filter group III of type II with cut-off frequency.

40 This group consists of elements similar to those of group II designated by the same reference letters. Finally, since the characteristic of these filters is for open-circuit operation, a further triode 17 permits obtaining at the terminals of resistance 18 the amplified and filtered potential. It will be understood that resistance 18 is not indispensable, if the useful impedance permits the flow of the direct current of the plate. It will also be understood that, although the same reference numerals have been used for electrical elements having identical functions, their numerical values or sizes may differ, indeed, must be different as will hereinafter be seen.

50 For instance, filter group III will preferably have to be designed for cut-off frequencies differing from those of group II, and the values of the parameters of the capacities and inductances 7, 8, 9, 10, 14, 15 will be different from the three stages. It is also obvious that the order of the stages as well as their number may be modified. For instance, the first filter group could have been of the frequency cut-off type. Resistances 6 and 18 could, finally, be replaced by choke-coils, and these could be regarded as practically infinite impedances inside the filtering zone. It must nevertheless be noted that, if the variable resistances 6 are dispensed with and replaced by choke-coils, it is necessary to provide means for regulating the negative biases of the grids of triodes 2, 11, 16 so as to make the plate resistance of the critical value adapted to obtain the desired filter effect. It is evident that four-electrode tubes could be employed (that is, two-grid tubes or screen-grid tubes).

The reactions and interactions, taking place in the structure, and determining the values of the different parameters of the inductances and capacities, are so involved as to make it desirable to use mathematical formulæ to elucidate the laws governing the phenomena taking place in the structure, and particularly to facilitate the design of the electric wave filtering groups of this invention whereby anyone, skilled in the art, may construct the same.

80 For this purpose, the filter group in type I may be represented mathematically by Fig. 2, where L and C denote elements 9 and 10 of Fig. 1 (inductance and capacity), and

$$\frac{L}{\alpha}$$

85 and $C\alpha$ denote elements 7-8, Fig. 1 (where α is a number). This group results in an attenuation curve as a function of the frequency represented in Fig 3 (e and V respectively denoting the input and output potentials, and f the frequency).

90 Also the complex filter group II may be mathematically represented by Fig. 4, where the additional elements $m C$ and

$$\frac{L}{m}$$

95 represent elements 14 and 15, Fig. 1 (m is an integer). This group results in an attenuation curve having a general shape as shown in Fig. 5. In Figs. 2 and 4, finally, R denotes the reduced resistance due to the parallel connection of regulating resistance 6, and the internal dynamic resistance of the amplifier triode. The denotations used show that the circuits, 7, 8, 9, 10, 14, 15 are all tuned to the same frequency which shall be designated by f_0 .

100 Referring to Fig. 5 which shows the attenuation curve for the most general case of the filter group type II, it will be noted that starting from f_0 where the ratio

$$\frac{V}{e}$$

105 is unity, this relation both for increasing as well as for decreasing frequencies, begins to grow, then crosses unity again, drops to zero, and then grows again to a liminal value.

110 The passing or transmitted band shall be called the frequency interval comprised between the extreme points where the value of the function

$$\frac{V}{e}$$

115 is equal to unity. Furthermore, $\delta\phi$ is the frequency interval separating two maximum values; δF , the frequency interval between two cut-off frequencies, while δf shall denote, generally speaking, the frequency interval between two symmetric points about f_0 having the same value of V .

120 Fig. 5 shows three values of δf found under different conditions (between the two maxima, between the two cut-off frequencies, and beyond the latter). In the case of Fig. 3, δF is infinitely high so that the graph tends asymptotically towards zero, for zero and infinite frequency. It is finally easy to demonstrate mathematically that all of the above frequency intervals admit as a geometric medium frequency f_0 , in other words, all of these intervals are delimited by two frequencies whose average is f_0 .

A mathematical study of the filter group type I then leads to the following results:
Denoting by β the quantity

$$5 \quad \frac{R}{L\omega_0},$$

in other words, the relationship between resistance R and reactance $L\omega_0$ of the inductance L at pulsation ω_0 corresponding to frequency f_0 , the 10 attenuation curve of Fig. 3 depends only upon quantity $\beta^2\alpha$ which shall be designated by A ($A=\beta^2\alpha$). It thus turns out to be a parameter defining quite correctly and definitely the filtering curve; it is moreover a simple number without 15 dimensions.

If A is higher than, or equal to 2, no pass band is present,

$$20 \quad \frac{V}{e}$$

decreasing as f_0 is departed from. On the contrary, if starting from $A=2$, the value of A falls off, an increasingly wider band is obtained, the 25 two humps of the graph become farther removed and rise at the same time; in other words, the filtering range becomes wider and more efficient. The maximum of

$$30 \quad \frac{V}{e}$$

is given by the expression:

$$35 \quad \left(\frac{V}{e}\right)_{\max} = \frac{2}{\sqrt{A(4-A)}} \quad (1)$$

and the value of the corresponding band is given by the expression:

$$40 \quad \frac{\delta f_1}{f_0} = \sqrt{(2-A)\alpha} \quad (2)$$

where α and f_0 occur. Still the general expression which connects

$$45 \quad \frac{V}{e}$$

and

$$\frac{\delta f_1}{\delta f}$$

50 depends only upon A and has this form:

$$55 \quad \left(\frac{V}{e}\right)^2 = A(2-A)\left(\frac{\delta f}{\delta f_1}\right)^2 + \left[1 - (2-A)\left(\frac{\delta f}{\delta f_1}\right)^2\right]^2 \quad (3)$$

a formula which contains in the second member only A and the variable quantity

$$\frac{\delta f}{\delta f_1}.$$

60 By way of example, Formulas 1, 2 and 3 show that for $A=1.4$ the practical mean value

$$\left(\frac{V}{e}\right)_{\max}.$$

65 is equal to 1.045 (Equation 1), the amplitude is reduced to 0.2 for a band $\delta f=2.94\delta f_1$ (Equation 3). If, moreover, $\alpha=0.1$ the band passed will be

$$70 \quad \frac{\delta f_1}{f_0} = 0.245.$$

The practical values to be admitted for A , range between 0.8 and 2. Indeed, for $A=0.8$, Formula 75 (1) results in

$$\frac{V}{e} = 1.25;$$

in other words, the humps reach as high a value as 25%. In the presence of a single stage this value would still be acceptable, but it becomes prohibitive rapidly in the presence of a plurality of consecutive stages. Finally, the value of β necessary in the calculation of the constants is given by this equation:

$$80 \quad \beta = \sqrt{A - (2 - A)} \frac{f_0}{\delta f_1} \quad (4) \quad 85$$

Hence, the invention discloses all of the means required to determine the electrical values to be chosen for the various elements in accordance with such results as may be desired.

The mathematical study of the filter group type II with "cut-off" frequency evidently is far more complicated. Also, in this instance, it is possible to define a number A , though the latter is no longer associated in the same way with the physical constants, but as before it defines the filter action and has a range for all practical purposes, between 0.8 and 2. The graph shown in Fig. 5 is then given strictly by this equation:

$$90 \quad \left(\frac{e}{V}\right)^2 = A(2-A) \left[\frac{1 - \left(\frac{\delta f_1}{\delta F}\right)^2}{1 - \left(\frac{\delta f}{\delta F}\right)^2} \right]^2 \left(\frac{\delta f}{\delta f_1} \right)^2 + \\ 100 \quad \left[1 - (2-A) \left(\frac{\delta f}{\delta f_1} \right)^2 \times \frac{1 - \left(\frac{\delta f_1}{\delta F} \right)^2}{1 - \left(\frac{\delta f}{\delta F} \right)^2} \right]^2 \quad (5) \quad 105$$

110 in which, apart from the variable δf , there occur only the known frequency intervals δf_1 and δF (given by the problem) and the quantity A .

If F designates the upper cut-off frequency corresponding to the limit of band δF , and if β has the same denotation and significance as before, determination of the electrical values to be chosen for these elements is possible as soon as A has been chosen on the basis of the following relations:

$$120 \quad m = \left(\frac{F}{f_0}\right)^2 \quad (6)$$

$$125 \quad \alpha = \left(\frac{\delta f_1}{f_0}\right)^2 \times \frac{1}{2-A} \times \frac{1 + \left(\frac{F}{f_0}\right)^2}{\left(\frac{\delta F}{f_0}\right)^2 - \left(\frac{\delta f_1}{f_0}\right)^2} \quad (7)$$

$$130 \quad \beta = \sqrt{A(2-A)} \frac{f_0}{\delta f_1} \times \frac{\left(\frac{\delta F}{f_0}\right)^2 - \left(\frac{\delta f_1}{f_0}\right)^2}{1 + \left(\frac{F}{f_0}\right)^2} \quad (8)$$

135 It is easy to understand that Formulas 5, 7, 8 become identical to Formulas 3, 2, and 4 whenever δF tends to assume an infinitely high value, in other words, when changing from the filter group type II to type I.

140 It can, also, be easily seen, respecting the filter group I, that in a filter amplifier designed in accordance with this disclosure, the value of resistance R plays a very critical part. Since α is defined by the relation of capacities 7 and 10 and is a constant for a finished filter amplifier, if R varies, β varies and as a consequence also A , since $A=\beta^2\alpha$. When A varies, also the width of the pass or transmissible channel is altered (Equation (2)). Using again the example before cited, and supposing that the value $A=1.4$ is attained

for $R=5000$ ohms, it is possible to draw up the following tabulation:

	R	A	$\frac{\delta f_1}{f_0}$	$(\frac{V}{e})_{\max}$
5	5,980	2.	0.000	1.
	5,660	1.8	0.140	1.005
	5,340	1.6	0.200	1.02
	5,000	1.4	0.245	1.045
	4,630	1.2	0.273	1.09
	4,230	1.	0.315	1.16
10	3,800	0.8	0.347	1.25

This table shows the inter-dependence of resistance R and the filtering characteristics.

15 Summarizing my invention, it will thus be seen that I have constructed and arranged a filter amplifier system having the characteristics of a band filter, and including tubes having three or more electrodes, the connection between the tubes being established by means of filtering groups comprising impedance net works or chains connected in series with the internal resistance of each tube. Optionally a regulating resistance is connected from the output circuit of each tube 20 between successive tubes as shown in the drawing. Two types of filters are provided, and the internal resistances of the tubes and the regulating resistances play in these types of filters a fundamental part. Another essential feature of 25 this type of filter system resides in the fact that the successive filter groups are closed upon a very high impedance, or even an infinitely high impedance, in other words, that they furnish no energy. That is to say, when it is stated that a filter group does not deliver any energy, this fact is approximately true since the output of the 30 group is connected between the grid and filament of a tube, it being noted that the latter furnishes the energy through the anode battery of the amplifier.

Although in what precedes, the assumption has been made that all of the circuits were tuned to the same frequency, it may be of interest or desirable in certain instances, to tune them or make them responsive to slightly different wave-lengths so as to insure certain additional effects, for instance, a slight change in the position of a cut-off frequency.

45 While I have indicated and described only one system for carrying my invention into effect, it will be apparent to one skilled in the art that my invention is by no means limited to the particular organization shown and described, but that many modifications in the circuit arrangement used, as well as in the apparatus employed, may be made without departing from the scope of my invention as set forth in the appended claims.

50 What I claim is:

1. In a thermionic tube amplifier, at least one filtering group comprising a tube, a resonant circuit, composed of a capacity and an inductance in series and connected between the plate of said tube and the grid of a second tube, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected across the grid-filament space of the said second tube.

65 2. In a thermionic tube amplifier, at least one filtering group comprising a tube, a resonant circuit connected in series with the internal resist-

ance of the tube and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected across a very high impedance, the complex circuit being connected with said resonant circuit, all circuits constituting the filtering group being tuned at the same frequency equal to the geometric mean of frequencies of the filtering group.

70 3. In a thermionic tube amplifier, at least one filtering group comprising a tube, a resonant circuit in series with the internal resistance of the tube, a resistance connected in parallel to said internal resistance, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected across a very high impedance connected with said resonant circuit.

75 4. In a thermionic tube amplifier, at least one filtering group comprising a tube, a resonant circuit in series with the internal resistance of the tube, a variable resistance connected in parallel to said internal resistance, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected across a very high impedance connected with said resonant circuit.

80 5. In a thermionic tube amplifier, at least one filtering group comprising a tube, a resonant circuit in series with the internal resistance of the tube, a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected across the grid-filament space of a second tube.

85 6. In a thermionic tube amplifier, at least one filtering group comprising a tube, a resonant circuit in series with the internal resistance of the tube, a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected across the grid-filament space of a second tube, each branch being tuned at a cut-off frequency of the filtering group.

90 7. In a thermionic tube amplifier, at least one filtering group comprising a tube, a resonant circuit in series with the internal resistance of the tube, a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected across the grid-filament space of a second tube, each branch being tuned at a cut-off frequency of the filtering

group, and the middle of the two cut-off frequencies being equal to the geometric mean of frequencies of the filtering group.

8. A filter group comprising a space discharge tube, an ohmic resistance in the tube output, a tuned circuit consisting of an inductance and a capacity in series, and connected in series with the said ohmic resistance and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected in shunt relation to the terminals of said assembly.

9. In a filter, at least one filter group comprising an ohmic resistance, a resonant circuit constituted by an inductance and a capacity in series, and connected in series with the said ohmic resistance, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected in shunt relation with the terminals of the assembly, an impedance appreciably larger than the surge impedance of the filter being connected between the output terminals of the said group.

10. A filter group comprising a thermionic tube, a high impedance across the tube output, a resonant circuit constituted by an inductance and a capacity in series and inserted in the anode circuit of the said tube, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected in shunt relation across the terminals of the group.

11. A filter group comprising a thermionic tube,

an ohmic resistance shunting the anode filament space of the said tube, a resonant circuit consisting of an inductance and a capacity in series and included in the anode circuit of the tube, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected in shunt relation across the terminals of the group.

12. A filter group, comprising a thermionic tube, a variable ohmic resistance shunting the anode filament space of said tube, a resonant circuit constituted by an inductance and a capacity in series, and included in the anode circuit of the said tube, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected in shunt relation across the terminals of the group.

13. In a thermionic amplifier, at least one filter assembly, comprising a thermionic tube, an ohmic resistance shunting the anode filament space of said tube, a resonant circuit constituted by an inductance and a capacity in series and connected in the anode circuit of this tube, and a complex anti-resonant circuit composed of two resonant branches in parallel, each branch comprising an inductance and a capacity in inverse order, the inductance of each branch being in resonance with the capacity of the other branch to the natural period of the anti-resonant circuit, this circuit being connected in shunt relation across the terminals of the assembly, the grid filament circuit of another thermionic tube being connected across the output terminals of the said assembly.
